FRED E. ASELTINE, OF DAYTON, OHIO, ASSIGNOR, BY MESNE ASSIGNMENTS, TO DELCO PRODUCTS CORPORATION, OF DAYTON, OHIO, A CORPORATION OF DELAWARE

CHARGE FORMING DEVICE

Application filed June 20, 1928. Serial No. 286,976.

This invention relates to charge forming devices for internal combustion engines, more particularly to such devices which are provided with a plurality of primary mixing chambers, each of which is adapted to supply a primary mixture of fuel and air to one of a plurality of secondary mixing chambers located adjacent the engine intake ports and in which additional air may be mixed 10 with the primary mixture under certain operating conditions.

An example of a charge forming device of this character is shown in the copending application of F. E. Aseltine et al., Serial No. 15 221,371, filed September 22, 1927, which matured to patent 1,819,495 granted Aug. 18, 1931.

It is an object of the present invention to provide simplified and improved means for 20 controlling the mixture proportions which shall be effective to form a mixture having the proportions of fuel and air which will most satisfactorily operate the engine under all possible operating conditions.

25 It is a further object of this invention to provide means for controlling the flow of fuel in accordance with the engine speed, and manifold suction, and which may be designed to produce a mixture of any desired proportions 30 under varying conditions of speed and load.

According to the present invention these objects are accomplished by the provision of a collapsible bellows connected to the manifold between the throttle and the engine by 35 a suction connection and connected by a link to a cam, which operates a fuel valve through an intermediary lever and is so contoured that the valve is opened as the manifold suction falls on opening of the throttle to increase the engine speed, or on increase of load 40 with a fixed throttle opening. While the cam is preferably contoured to maintain the mixture proportions substantially constant on changes of speed due to changes in throttle 45 position it may be designed to give a mixture richer or leaner than normal at any point in the entire speed range of the engine: for instance the cam may be so shaped as to give a sudden increase in fuel flow at high speed, 50 say that corresponding to a vehicular speed

of 45-50 miles per hour on the level in order to give the desired power for high speed operation. Further the cam is designed to give a richer mixture on increase of load with fixed throttle.

Further objects and advantages of the present invention will be apparent from the following description, reference being had to the accompanying drawings, wherein a preferred form of embodiment of the present invention is clearly shown.

In the drawings:

Fig. 1 is a vertical, longitudinal section through the carburetor unit and the middle outlet branch of the manifold.

Fig. 2 is a vertical lateral section on the line 2—2 of Fig. 1.

The device disclosed herein comprises a main air manifold indicated in its entirety by the reference numeral 10 and having three outlet branches the middle one of which 12 is shown herein. Each of these branches communicates with one of the intake ports 14 of an internal combustion engine, each of which serves two adjacent cylinders as disclosed in the copending applications above referred to. Each of the manifold branches is provided with an attaching flange 16 for attaching the manifold to the engine block in the usual way, and a flange 18, to which the carburetor unit may be secured is provided adjacent the manifold inlet.

The carburetor unit comprises a main housing 20 having an attaching flange 22 secured by screws 24 to the flange 18. An air inlet horn 26 is secured by screws 28 to the main housing and communicates with an opening in the top wall of said housing. A casting 30 having certain fuel passages and a dash pot cylinder formed therein is secured by screws 32 to the bottom of the main housing, and a sheet metal fuel bowl 34 is held tight against an annular shoulder 36 formed on a skirt 38 depending from the main housing by a screw 40 screwed into the casting 30, a suitable gasket being provided to prevent leakage around the screw.

Fuel is conducted from a main source of supply to the fuel bowl and the flow is controlled by a float (not shown) in the usual

manner to maintain a constant level in the bowl. To convey fuel from the bowl to a plurality of primary mixture passages 42, hereinafter more fully described, a passage 44 is provided in the casting 30. A port 46 connects this passage with the fuel bowl and flow through such port is regulated by a tapered fuel valve 48 which is slidable in a bore 50 in casting 30 and cooperates with a seat 52 formed where the passage 44 joins the bore 50. This valve is controlled by mechanism described hereinafter, to regulate the proportions of fuel and air in the mixture as desired. The passage 44 connects with a horizontal fuel canal 54 at its upper end and said canal communicates with three pairs of calibrated low and high speed jets or plugs 56 and 58 respectively, each of these pairs of jets being adapted to convey fuel to one of the mixture passages 42 in a manner later described.

Fuel is lifted from the fuel bowl to the primary mixture passages by the suction therein. When the throttle is moved toward a closed position to reduce the engine speed this suction may be reduced sufficiently to allow the fuel column between the bowl and the jets to drop enough to temporarily starve the engine unless means were provided to prevent this action. To prevent this action a check valve 60 is provided, which is normally lifted above an annular rim 62, surrounding the outlet of passage 44, by the suction, but on reduction of suction immediately seats on said rim preventing downward flow through the passage 44. A two stage metering valve 64 of the type shown in the above mentioned applications and operating in the same way, is provided in the passage 44.

The primary mixture passages 42 to which the pairs of jets 56 and 58 deliver fuel are bored horizontally through the central part of the main housing 20, are parallel to each other and relatively close together as indicated in the drawings. Air is admitted to each of the primary mixture passages through an air inlet bushing 66 screwed into the outer end of the primary mixture passage. Immediately posterior to said bushing a small Venturi tube 68 is received in an enlargement 70 of the primary mixture passage. Each of the Venturi tubes is provided with two external ribs 72 arranged circumferentially of the tube and fitting tightly in the enlargement 70. These ribs form between them a fuel channel 74 with which the low speed jet 56 communicates, and a series of orifices 76 are provided in the Venturi tube to connect the interior of the tube with the said channel.

The Venturi tube 68 is reduced in size at its inner end and is spaced from the wall of the mixture passage as shown in Fig. 1. This space 78 is substantially a dead air space 85 in which the suction or partial vacuum is

substantially the same as that maintained in the mixture passage between the end of the Venturi tube and the throttle, which controls flow through the mixture passage and is more fully described hereinafter. Each main fuel nozzle 58 terminates in the wall of the mixture passage 42 with which it is associated at a point opposite the reduced inner end of the venturi so that fuel flows therefrom into the space 78 and the suction in said space controls the flow of fuel. It will be clear that the suction within the Venturi tube 68, which is effective to cause a flow of fuel through the low speed jet 56 and orifices 76 communicating therewith, is greater than that effective to cause a flow through the jet 58. Hence each jet 56 is effective to supply fuel to its associated mixture passage at low speed when the suction in the mixture passage is relatively low while the main or high speed jet supplies no fuel until a higher engine speed has been reached. The jets 56, therefore, are effective to supply fuel to the mixture passages at all speeds and under all operating conditions, supplying all of the fuel for idling and low speed operation and a part of the fuel at all other times, while the main or high speed jets are not effective to supply any fuel to the mixture passages until the engine is running at a speed corresponding substantially to a vehicular speed of 20-25 miles per hour for example. The operation and construction of the fuel jets is more fully described in my copending application Serial No. 288,684, filed June 27, 1928, in which such structure is claimed.

The flow of the primary mixture through the passages 42 is controlled by a single throttle valve 80 which extends across all of the passages 42 and has grooves 82 therein which register with said passages. The means for operating this throttle forms no part of the present invention but is fully disclosed in the said patent 1,819,495. Each primary mixture passage communicates with a pipe associated with each branch of the manifold for conveying the primary mixture to the secondary mixing chambers. The pipe 84 associated with the middle outlet branch 12 of the manifold is shown herein and those which convey primary mixture to the other branches of the manifold are fully shown and described in the above mentioned applications, such structure forming no part of the present invention.

All of the air which is mixed with the primary mixture in the secondary carburetors is admitted through the air horn 26, the flow being controlled by an air valve 86 normally held against a seat 88 by a spring 90. Air passing the valve flows first into an air chamber 92 and thence through a secondary air passage 94 communicating with the inlet end of the air manifold and provided with a

throttle valve 96 secured to a shaft 98 journalled in the housing 20, and operated in a manner briefly described hereinafter to regulate the flow of air to the secondary mixing chambers.

5 The spring 90 is received between the air valve and a flange 100 projecting from a sleeve 102, slidable on a guide sleeve 104 which guides the air valve stem in the manner described in the above mentioned applications. The choke mechanism, which is not shown herein, is adapted to be operated to lift the flange fully to bring sleeve 102 into engagement with the air valve to hold said valve closed to facilitate starting, or partially to increase the tension of the spring holding the air valve closed. To prevent sufficient opening of the air valve to cause leaning of the mixture and to prevent fluttering of said valve a dash pot 106 is provided which may be of the form shown in either of the copending cases referred to or may be of any conventional or desired design.

10 The throttle operating mechanism forms no part of this invention and is not shown herein, but for the purpose of facilitating understanding of the operation of the whole device the mode of operation of the throttles 80 and 96 will be very briefly described. 15 During operation at all speeds up to a vehicular speed of 20-25 miles per hour it is desirable that the primary mixture passages supply all the combustible mixture to the engine cylinder, and at speeds higher than that to admit air to the secondary mixing chambers through the passage 94. To secure this result the two throttles 80 and 96 are provided with a common operating mechanism so arranged that the primary throttle 80 is given 20 a predetermined movement before the throttle 96 begins to open and after said throttle 80 begins to open both throttles move together to wide open position.

25 There are three secondary mixing chambers of identical construction, each of which comprises a Venturi tube 110 secured in an outlet branch of the manifold in such position that its point of greatest depression is immediately adjacent the outlet end of the primary mixture pipe associated with that particular manifold branch, as shown in Fig. 1. Each venturi is provided with an external circumferential rib 112 which, when the device is assembled, is adapted to be clamped 30 between shoulders 114 and 116 on the manifold and engine block respectively. The Venturi tubes cause the air passing the ends of the primary mixture delivery pipes to move at high velocity creating in each tube 35 a high suction during all operating conditions.

The novel means to control the flow of fuel through the passage 44 in accordance with the engine suction and speed will now be described. The tapered fuel valve 48 previous-

ly described is provided at its upper end with a flat extension 120 which is received between the two arms 122 of a bifurcated lever 124 pivoted at 126 in a support 128 depending from the housing 20, the valve being connected to the lever by a pin 130, received in slots 132 in the arms 122. A roller 134 is rotatably mounted on the other end of lever 124 and is engaged by a cam 136, operated in a manner later described, to open the fuel valve which is normally held closed by a spring 138 connected to the lever 124 and a bracket 140 projecting from the housing 20. The bracket 140 also supports the cam 136 which is pivoted on a pin 142 projecting from the bracket, a nut 143 preventing lateral movement of the cam.

15 The cam is operated in accordance with variations in suction in the manifold by means of an expandible metal bellows 144, of the type generally known as a sylphon, the upper end of which is secured to a supporting member 146 integral with and projecting from the housing 20 while the lower end of the bellows is free, permitting the bellows to expand and contract as the manifold suction varies, such suction being communicated to the bellows through a pipe 148 which is connected to the manifold inlet by means of a union 150, one part of which is screwed into the manifold between the throttle 96 and the engine as shown in Fig. 1. Connected with the lower end of the bellows and moving with the latter as it expands and contracts is a rod 152 guided in an adjustable sleeve or collar 154 screwed into a part of the supporting member 146 and provided with a knurled head 156 by means of which it may be adjusted. The lower end of the rod is connected by a pin and slot connection 158 to the cam 136 and a compression spring 160, received between the collar 154 and a flange 162 secured to the rod at its lower end, tends to push the rod down and rotate the cam in a clockwise direction in Fig. 2. The rod will come to rest when the force of the spring tending to lower the rod is balanced by the force of the manifold suction tending to lift the rod through the medium of the metal bellows. By adjusting the collar 154 the force of the spring may be varied and hence the position of the cam at idling and other engine speeds may be varied, varying the amount of opening of the fuel valve at 20 idling and other engine speeds.

25 The operation of the above device will now be described. Let it be assumed that the engine is not operating. There is no suction or partial vacuum in the manifold to oppose the action of spring 160 and said spring, being more powerful than spring 138 will rotate the cam 136 in a clockwise direction bringing the high point of the cam into engagement with the roller 134 and opening the fuel valve 48 against the tension of spring 30

138. The engine suction at points posterior to the throttle 96 is highest when the carburetor is choked to start, or is operating at low speed with throttle 96 closed, so that as soon as the engine is started and is operating at low speed the suction collapses the metal bellows, rotating the cam 136 counter clockwise and allowing the spring 138 to move the fuel valve 48 toward its closed position. Under these operating conditions the cam is moved to a position where the lowest point of the cam engages the roller 134 and spring 138 moves the fuel valve 48 almost to its closed position.

15 If, now, it be desired to increase the speed of the engine the throttle 80, or throttle 96, or both, are opened depending on whether the increase in speed is to be great or small, and on increase of speed it is desirable to increase the amount of fuel supplied to the mixture passages. On opening movement of either or both throttle valves the manifold suction which is communicated to the pipe 148 falls permitting expansion of the metal bellows 144 and a clockwise movement of the cam 136 which opens the valve against the tension of spring 138 until a condition of balance of the forces effective to move the cam 136 in opposite directions is reached. If either, or both the throttles are open and a closing movement of one or both takes place to reduce the speed the action is the reverse of that above described. The cam is moved counter clockwise by a contraction of the metal bellows to permit a closing movement of the fuel valve.

Changes in load with a constant throttle setting will effect changes in the suction maintained in the manifold and will result in variable positioning the fuel valve in accordance with the load. For instance it may be assumed that an automobile is running on a level at any given speed, say 35 miles per hour. If an up grade is reached the load increases, the engine slows down and the manifold suction decreases as the engine speed decreased. The decrease in suction causes expansion of the metal bellows and opening of the fuel valve as previously described, to form a richer mixture which is necessary to properly operate the engine on heavy load. If, on the other hand, the automobile reaches a down grade, the engine speed increases due to the lighter load, the manifold vacuum increases and the metal bellows is collapsed to effect counter clockwise movement of the cam 136 and closing movement of the fuel valve.

While the form of embodiment of the present invention as herein disclosed, constitutes a preferred form, it is to be understood that other forms might be adopted, all coming within the scope of the claims which follow.

What is claimed is as follows:

1. A charge forming device for an internal combustion engine having in combination a

mixture passage, means for supplying fuel and air thereto, a throttle, means for varying the amount of fuel in said mixture comprising a cam adapted to variably control the fuel admission as the cam is moved to 70 different positions and means for moving the cam in accordance with variations in engine speed and load.

2. A charge forming device for an internal combustion engine having in combination 75 a mixture passage, means for supplying fuel and air thereto, a throttle, a fuel valve for variably regulating the flow of fuel to the mixture passage, a cam for variably positioning the fuel valve as the cam is moved to different positions, and means for moving the cam in accordance with variations in engine speed and load.

3. A charge forming device for an internal combustion engine having in combination 85 a mixture passage, means for supplying fuel and air thereto, a throttle, a fuel valve for variably regulating the flow of fuel to the mixture passage, a cam for variably positioning the fuel valve, a pressure responsive device for operating the cam and means for communicating the pressure maintained within the mixture passage to said pressure responsive device.

4. A charge forming device for an internal combustion engine having in combination a mixture passage, means for supplying fuel and air thereto, a throttle, a fuel valve for regulating the flow of fuel to the mixture passage, a cam for variably positioning the fuel valve, a pressure responsive device for operating the cam and a suction passage connecting the pressure responsive device with the mixture passage at a point posterior to the throttle.

5. A charge forming device for internal combustion engines comprising a mixture passage, means for supplying fuel and air thereto, a throttle, a suction operated metering valve subject to the suction in the mixture passage anterior to the throttle for controlling the flow of fuel, and an additional fuel valve subject to substantially the same suction as is maintained in the intake manifold.

6. A charge forming device for internal combustion engines comprising a plurality of primary mixture passages adapted to supply fuel air mixture to a plurality of secondary mixing chambers, means for supplying fuel and air to said primary mixture passages, a single secondary air passage supplying auxiliary air to all of the secondary mixture passages, and means for varying the flow of fuel to said primary mixing chambers in accordance with variations in suction in said secondary air passage.

7. A charge forming device for internal combustion engines comprising a mixture

- passage, an air inlet therefor, a plurality of fuel inlets therefor, a plurality of restrictions each of which is adapted to regulate the flow of fuel through one of said inlets, a fuel passage supplying fuel to all of said fuel inlets, a valve for regulating the flow through said passage, a mixture throttle, an air throttle and means operated in accordance with the suction posterior to said air throttle for operating said valve. 8. A charge forming device for internal combustion engines comprising a primary mixture passage, a fuel passage for supplying fuel and air thereto, a secondary mixing chamber into which the primary mixture passage delivers, a passage supplying air to the said secondary mixing chamber, means for controlling the flow through said fuel passage comprising a plurality of valves, one of which is subject to the suction in the primary mixture passage and the other of which is controlled by the suction in the passage supplying air to the secondary mixing chamber. 9. A charge forming device for internal combustion engines comprising a mixing chamber, means for supplying fuel and air thereto, a secondary air passage supplying additional air, and means for regulating the flow of fuel to the mixing chamber, said means being controlled by the suction in the mixing chamber and in the secondary air passage. 10. A charge forming device for internal combustion engines comprising a mixing chamber, means for supplying fuel and air thereto, a secondary air passage supplying additional air, and a plurality of means for regulating the flow of fuel to the mixing chamber, one of said means being controlled by the suction in the mixing chamber and the other of said means being subject to the suction in the auxiliary air passage. 11. A charge forming device for internal combustion engines comprising a mixture passage, means for supplying fuel and air thereto, a mixture throttle controlling the flow of mixture therethrough, a secondary air passage supplying additional air, an air throttle controlling the flow of air therethrough, a fuel valve for regulating the flow of fuel to the mixture passage, and pressure responsive means for controlling the position of the fuel valve, said means being controlled solely by the suction in the secondary air passage. 12. A charge forming device for internal combustion engines comprising a mixture passage, means for supplying fuel and air thereto, a mixture throttle controlling the flow of air therethrough, a secondary air passage supplying additional air, an air throttle in the secondary air passage, means for varying the amount of fuel supplied to said mixture passage comprising a pressure responsive device and means for communicating the pressure of the secondary air passage at points posterior to the throttle to said pressure responsive device.
